ATTORNEY

UNITED STATES PATENT OFFICE.

EARL E. EBY, OF WILKINSBURG, PENNSYLVANIA, ASSIGNOR TO WESTINGHOUSE ELECTRIC AND MANUFACTURING COMPANY, A CORPORATION OF PENNSYLVANIA.

VACUUM-TIGHT SEAL.

1,223,777.

Specification of Letters Patent. Patented Apr. 24, 1917.

Application filed July 6, 1915. Serial No. 38,119.

To all whom it may concern:

Be it known that I, EARL E. EBY, a citizen of the United States, and a resident of Wilkinsburg, in the county of Allegheny and State of Pennsylvania, have invented a new and useful Improvement in Vacuum-Tight Seals, of which the following is a specification.

My invention relates to methods of and means for producing vacuum tight seals between closely fitting members, such as are required, for example, between the body and the cover of a metal-case vapor converter, and it has for its object to provide a device of the character specified which shall be simple and inexpensive to manufacture and highly effective in operation.

In the accompanying drawing, Figure 1 is a sectional view of a portion of a vapor converter, together with a vapor-spraying device for applying a cohesive coating thereto; Fig. 2 is a sectional view of a finished seal constructed in accordance with one form of my invention; and Fig. 3 is a sectional view of a finished seal embodying a modification of my invention.

In the manufacture of exhausted containers of large size, such, for example, as are employed in connection with vapor converters of the metal-case type, it is necessary to employ a plurality of closely fitted and coacting members with sealing means applied to the joints therebetween. It has hitherto been common practice to seal joints of the character specified by means of mercury or organic materials, such, for example, as shellacs, gums, waxes or resins. It has been found to be a somewhat difficult matter to obtain such a close mechanical fit between the various members of a container of the character specified that, under the influence of great temperature ranges, small spaces were not opened up, through which the sealing material was drawn into the container, with subsequent vaporization and harmful effects upon the vacuum. I have found that, by the use of a metal spray, wherein a small wire or rod of any suitable material is fused and blown in any desired

direction, a thin, tough and closely adherent coating or bridge of metal may be provided across a joint of the character specified and, if suitable metals are chosen for the material of the spray, a tight seal results. If, for closer coherence with the body

of the container, it is desired to employ a material for the spray which is somewhat pervious or porous in nature in deposition, I find that, by subsequently applying a coating of sealing material, such, for example, as shellac or gum, over said metal bridge, a joint may be produced which is capable of withstanding considerable mechanical strain and which, at the same time, will not permit the passage of gas or organic material into the interior of the container.

Referring to the accompanying drawing for a more detailed understanding of my invention, I have shown the body of the container of a vapor converter or similar evacuated device at 4 in Fig. 1. A cover 5 is placed upon the container body 4 and is rigidly maintained in place thereupon by any suitable means, such, for example, as bolts or clamps (not shown). The joint between the members 4 and 5 is preferably hollowed out at its edge to form a V-shaped groove, as shown at 6. A metal spraying device 7, such as shown, for example, in U. S. Patent 1,128,175, issued to E. Morf, is then operated opposite the groove 6 to deposit a closely adherent film or layer of sealing material 8 therein, as shown in Figs. 1 and 2. Briefly described, the device 7 comprises an inner tube 9 through which a rod or wire 10 of the material to be deposited may be projected forward at any desired rate. The tube 9 is surrounded by a second tube 11 and a combustible gas of any desired nature is supplied through the annular space therebetween. A still larger tube 12 surrounds the tube 11, and air, under considerable pressure, is projected through the annular space thus formed. As a result, a concentric flame or blast is provided around the end of the wire 10, fusing the latter and projecting the substance thereof either in small particles or as a vapor in a spray 13. It has been found that, by properly adjusting the pressure and temperature of the flame and that, by the choice of suitable substances, the material of the spray 13 will be deposited to form a closely adherent coating.

It is frequently desired to employ, for the bridge or layer 8, a material which is deposited in a more or less porous state, and I find that, by applying a layer of shellac or gum thereover, as shown at 14 in Fig. 3, a seal may be produced having the essential

requisites of strength and tightness; it being found that the material of the layer 14 is not drawn through the pores of the layer 8 at the maximum obtainable vacuum.

5 I have shown the application of a sealing layer within a V-shaped groove because of the protection from mechanical injury and the self-locking effect attendant thereupon, but a sealing layer of the character de-
10 scribed may be applied with good results over joints of any character, provided suitable means are provided for preventing excessive lateral displacements between the two members to be joined.

15 I may, if found desirable, employ a spraying device in which the fusing heat is produced by an electric arc and, furthermore, I am not restricted to the use of metal as a spraying material but may employ glass
20 or any other suitable substance in this relation.

While I have shown my invention in several preferred forms, it will be obvious to those skilled in the art that it is susceptible
25 of various minor changes and modifications without departing from the spirit thereof and I desire, therefore, that no limitations shall be placed thereupon except such as are imposed by the prior art or are specifically set forth in the appended claims.

I claim as my invention:

1. The process for producing a vacuum-tight seal between two members which comprises bringing said members into close me-

chanical union and then spraying a layer 35 of metal over the line of contact.

2. The process for producing a vacuum-tight seal between two members which comprises bringing said members into close me-
30 chanical union and then depositing a layer 40 of metal over the line of contact by a fusing spray.

3. The process for producing a vacuum-tight seal between two members which comprises bringing said members into close me-
45 chanical union, spraying a layer of metal over the line of contact, and then covering said layer with a coating of sealing material.

4. The process for producing a vacuum-tight seal between two members which comprises bringing said members into close me-
50 chanical union, depositing a layer of metal over the line of contact by means of a fusing spray, and then covering said layer with a coating of sealing material.

5. A vacuum-tight container comprising a plurality of closely fitting members, and a layer of spray deposited metal over the lines of union thereof.

6. A vacuum-tight container comprising 60 a plurality of closely fitting members, a layer of spray deposited metal over the lines of union thereof, and a coating of sealing material over said metallic layer.

In testimony whereof, I have hereunto 65 subscribed my name this 28th day of June, 1915.

EARL E. EBY.
